SANITARY BELT

Curt Walter Leupold, Nurnberg, and Lorenz Hupfauf,
Furth, Germany

Application February 17, 1953, Serial No. 337,413

Claims priority, application Germany June 21, 1952

4 Claims. (Cl. 128—291)

This invention relates, as indicated, to sanitary belts.

Sanitary belts of a type commonly available are usually made of a woven rubberized fabric which, in use, bears against the skin of the wearer and causes chafing.

These belts are usually provided with supporter straps, which bear the loops or other fasteners to which the ends of the strip of material which carries the sanitary pad are secured, and these straps are secured to the interior surface of the sanitary belt, thereby adding to the discomfort of the wearer, since the portions of the straps thus secured project inwardly into the flesh of the wearer.

Moreover, in many of these belts, metallic elements such as the aforesaid loops, are secured to the belt or straps in such a manner that they too lie against the skin, thereby further adding to the discomfort of the wearer. One form of existing loop has an inwardly directed point to which the strip of material to which reference has been made is attached in such a manner that it is hooked onto the point. The strip of material has a secure anchorage to said loop, but an inherent disadvantage is the fact that the strip of material has to be threaded through the narrow upper part of the loop in order that it may be laid over the point.

The present invention has as its primary object the provision of a sanitary belt of the character described which avoids chafing of the skin.

Another object of the invention is to provide a sanitary belt of the character described, in which the straps, which bear the loops or fasteners to which the ends of the sanitary napkin are secured, are applied and secured to the exterior of the belt.

A further object of the invention is to provide a novel form of loop which avoids the disadvantages of existing loops in that it renders possible the insertion of the ends of the sanitary napkin into the loop from the bottom.

Other objects and advantages of the invention will become apparent during the course of the following description.

In the accompanying drawings, forming a part of this specification, and in which like numerals are employed to designate like parts throughout the same,

Fig. 1 is a perspective view of a sanitary belt embodying the novel features of the invention;

Fig. 2 is a fragmentary cross-sectional view taken on the line 2—2 of Fig. 1;

Fig. 3 is a front elevational view of one of the loops, and

Fig. 4 is a side elevational view of the loop of Fig. 3, as viewed from the right side of Fig. 3.

Referring more particularly to the drawing, reference numeral 3 designates a belt, which is preferably made from woven rubberized fabric, consisting of elastic threads having an especially strong textile covering woven therearound, the belt, after being woven, being roughened on its inner side or face so as to produce a fluffy layer or surface 4 on said inside face, which lies against the body of the wearer. This avoids chafing of the skin.

Secured to the outer surface of the belt 3 are straps 2, which are also made of a woven rubberized stretchable fabric, these straps having secured thereto the loops 1, to which the ends of the strip of material which contains the sanitary napkin are adapted to be secured. By securing the straps 2 to the exterior face of the belt 3, the

2

inner surface of the belt is freed from inwardly-projecting portions of the straps, thereby greatly increasing the comfort of the wearer.

The loops 1 are also secured to the exterior surface of the straps 2, as best shown in Fig. 1, so that they do not lie against the skin, thus further increasing the comfort of the wearer.

The loops 1 may be made of metal or a synthetic material, and each loop is bent to provide an upper portion of inverted U-shape and a lower portion of generally W-shaped contour, the outer arms of the W merging into the lower ends of the upper portion of the loop. The inner arms 5 and 6 of the W are slightly separated from each other, as best shown in Fig. 4. As stated above, the loops may be made of metal or a synthetic material. They may be made of wire or as shown in Figs. 3 and 4, of a strip of elastic material, in which case, they may be embossed to provide a reinforcing rib 7.

When a sanitary pad is to be secured to the loops 1, the ends of the strip of material which contains the sanitary pad are pressed upwardly through the space between the arms 5, 6, in the direction indicated by the arrow in Fig. 3, after which the ends of the strip are brought over and laid across the arms 5 and 6, which form a point to which said ends are hooked.

It is preferred that the material from which the loops 1 are made have strong, springy characteristics, although this is not essential, since the advantages of these loops 30 can also be attained when they are made of a rigid material. Where made of a springy material, the arms 5 and 6 can lie in abutment with each other, in which case, the ends of the strip of material can be pushed upwardly through the slit between said arms.

Due to the W-shaped form of the loop, and because of the weave of the strip of material which carries the sanitary napkin, it is impossible, even where a space exists between the arms 5 and 6, for the strip of material to be pulled out through said space, after the ends of the 40 strip have been anchored to the loops.

It is to be understood that the form of our invention, herewith shown and described, is to be taken as a preferred example of the same, and that various changes in the shape, size and arrangement of parts may be resorted to, without departing from the spirit of our invention, or the scope of the subjoined claims.

Having thus described our invention, we claim:

1. The method of making a sanitary belt of the character described, said method comprising roughening of the interior surface of a belt made of a woven elastic fabric in order to produce a fluffy interior layer.

2. A sanitary belt of the character described, said belt consisting of a woven fabric, the threads of which, on the interior surface of the belt, are roughened, whereby to produce a fluffiness on said surface which lies against the body of the wearer.

3. A sanitary belt of the character described, said belt consisting of a woven elastic fabric, the threads of which are covered with a textile which is roughened to produce a fluffiness on the interior surface of the belt which lies against the body of the wearer.

4. The method of making a sanitary belt of the character described, said method comprising roughening of the interior surface of a belt made of a woven fabric in order to produce a fluffy interior layer.
